METAL ARROWHEAD

Wilton Hamilton, 733 S. 31st St.,
South Bend, Ind. 46615

Filed Aug. 19, 1974, Ser. No. 498,713

Term of patent 14 years

Int. Cl. D22—03

U.S. Cl. D22—12

Fig. 1

Fig. 2

Fig. 3

Fig. 5

Fig. 4

Fig. 6

FIG. 1 is a perspective view of a metal arrowhead embodying the present design;

FIG. 2 is an elevational view of one of the sides of the arrowhead;

FIG. 3 is an elevational view of the edge opposite that shown in FIG. 1;

FIG. 4 is an elevational view of the side opposite that shown in FIG. 2;

FIG. 5 is an elevational view of the front end; and

FIG. 6 is an elevational view of the rear end.

I claim:

The ornamental design for a metal arrowhead, substantially as shown.
